(57) **CLAIM**

The ornamental design for a combination eyeglass and personal articles holder, as shown and described.

DESCRIPTION

FIG. 1 is a front elevational view of a combination eyeglass and personal articles holder, showing my new design;

FIG. 2 is a front elevational view thereof, shown in use;

FIG. 3 is a rear elevational view of a combination eyeglass and personal articles holder;

FIG. 4 is a rear elevational view thereof, shown in use;

FIG. 5 is a top plain view of a combination eyeglass and personal articles holder;

FIG. 6 is a top view thereof, shown in use; and,

FIG. 7 is a top, front, and side perspective view a combination eyeglass and personal articles holder.

The broken lines shown in the drawings are for illustrative purposes only and form no part of the claimed design.
